EXHAUSTING METHOD AND APPARATUS

David N. Crosthwait, Jr., Marshalltown, Iowa, assignor to C. A. Dunham Company, Marshalltown, Iowa, a corporation of Iowa

Application April 17, 1935, Serial No. 16,803

9 Claims. (Cl. 230—92)

This invention relates to an improved method and apparatus for exhausting fluids, more particularly mixed gases and liquids, from one space and forcing them into another space against a higher pressure. More particularly the invention relates to an improved form of jet exhauster using water as the actuating fluid, and more particularly designed for withdrawing condensate and non-condensable gases from a heating system.

In the well known kinetic exhauster of this general type, a jet of water is projected under pressure from a nozzle through a portion of the space containing the fluids to be exhausted and thence into a restricted delivery tube, the fluid being entrained or drawn out with the liquid of the jet and carried into a separating tank from which the gases are vented. A portion of the water is then recirculated by means of a pump or similar apparatus through the jet to continue the exhausting process. According to the present invention a ring or lining of water is continuously maintained within the entrance portion of the delivery tube so as to form an elastic lining for the delivery tube or an enveloping wall of liquid through which the jet is projected. The fluids to be exhausted are entrained in the jet and between the jet and enveloping liquid wall, a portion of which is carried onward through the delivery tube with the liquid of the jet. The advantages of this method and apparatus will be explained in more detail hereinafter.

The particular object of this invention is to provide an improved method and apparatus for exhausting fluids, as briefly described hereinabove and disclosed more in detail in the specifications which follow.

Another object is to provide an improved kinetic exhauster using water as the actuating fluid which attains a high efficiency by obtaining a high ratio of air exhausted to the liquid streams furnishing the exhausting energy.

Another object is to provide an exhauster of this type in which the losses due to friction and changes of pressure are minimized by avoiding the inelastic impact of moving water particles on stationary surfaces by providing an enclosing wall of water which moves with the actuating jet.

Another object is to provide an elastic delivery tube into and through which the jet is projected.

Another object is to provide a method and apparatus which will cooperate with or compensate for changes in pressure caused by partial condensation of the vapor diffused through or be-

tween the water particles due to compression and also to the cooling action of the liquid streams.

Another object is to provide improved means for establishing and maintaining the wall of liquid which encloses the actuating jet.

Numerous other objects and advantages of this invention will be more apparent from the following detailed description of certain approved forms of apparatus designed and operating according to the principles of the invention.

In the accompanying drawings:

Fig. 1 is an elevation showing one form of the complete exhauster assembly, with parts broken away.

Fig. 2 is a partial side elevation and partial vertical section taken substantially on the line 2—2 of Fig. 3, showing one form of the jet exhauster.

Fig. 3 is a vertical section taken substantially on the line 3—3 of Fig. 2.

Fig. 4 is a diagrammatic vertical section illustrating the operation of one of the improved jet-exhauster units.

Fig. 5 is a vertical section, similar to Fig. 2, showing a modified form of the jet exhauster.

Fig. 6 is a vertical section on a somewhat larger scale taken substantially on the line 6—6 of Fig. 5.

Fig. 7 is a horizontal section taken substantially on the line 7—7 of Fig. 5.

Fig. 8 is a vertical section corresponding to the central portion of Fig. 5 but showing a modification.

Fig. 9 is partial vertical section showing still another modification.

Fig. 10 is a partial vertical section showing the use of a multiple jet.

Fig. 11 is a horizontal section illustrating the means for separately delivering water to each of the chambers enveloping a group of separate delivery tubes.

Referring first to Figs. 1, 2 and 3, the exhausting apparatus comprises in general the separating tank A which contains the supply of actuating liquid, preferably water, the pump B driven by the motor C, and the improved jet exhauster indicated generally at D. The rotary pump B, preferably of the centrifugal type, is rotated by motor C through shaft 1 and connection 2. The pump withdraws water from tank A through pipe connection 3 and forces this water through outlet 4 and manifold 5 into and through the nozzle or nozzles 6 of the jet exhauster. The jets are projected into and through a portion of the exhausting chamber 7 and thence into and through the delivery tubes 8 which discharge into pipe 9 leading back into the upper portion of

tank A. The fluids to be exhausted (usually mixed liquids and gases) are delivered through pipe connection 10 and strainer 11 into and through the pipe connection 12 provided with 5 one-way valve 13 and thence into the exhausting chamber 7. The valve 13 prevents the return of fluids from the higher pressure spaces into the low pressure space that has been exhausted when the exhausting apparatus is not in operation. 10 The exhausted fluids are carried along with the liquid of the actuating jet through the tubes 8 and pipe 9 into the tank A. The non-condensable gases are vented from tank A, but the supply of water in tank A will be gradually augmented by 15 the condensate or other liquid drawn into the tank. For the purpose of discharging this excess liquid from the tank, the pump manifold 5 is provided with a second discharge outlet 14 through the valve casing 15 into a discharge pipe 16 which leads to the boiler of the heating system or some other place of discharge. The valve 15 is normally closed but is automatically opened at intervals to permit the discharge of the excess liquid by means of a float-controlled mechanism 20 parts of which are indicated at 17, 18 and 19. The pressure gauges indicated at 20 and 21 indicate the pressures existing at the high and low pressure sides of the exhauster respectively, and the gauge 22 indicates the water lever in tank 25 A. The combination as thus far briefly described is substantially old and well known in this art, the present invention relating to improvements in the specific form of jet exhauster assembly indicated generally at D, several forms 30 of which will now be described more in detail.

Referring now more particularly to Figs. 2 and 3, the form of exhauster assembly here shown comprises two similar exhausting units each comprising a nozzle and delivery tube. The assembly 40 may comprise one or several of these units, each of which operates substantially independently, and for convenience the apparatus will be described as if only one unit were included. Each vertically positioned nozzle 6 is mounted in the 45 lower wall of casing 23 which encloses the exhausting chamber 7, so that the larger open lower end of the nozzle member will be in open communication with the manifold 5. The upper discharge portion of the nozzle is restricted as 50 at 24 so as to give added velocity to the jet, the extreme upper portion of the nozzle passage being somewhat flared outwardly so as to increase the dispersion of the jet as it is projected upwardly through the exhausting chamber 7. The 55 delivery tube assembly indicated generally at 8 is, as usual, provided with a flared lower inlet end 25 to receive the jet and fluids sucked or entrained with the jet liquid, an intermediate portion 26 of smaller diameter, and a flared upper portion 27 of increased diameter to decrease the 60 velocity of the stream before it is discharged into the delivery pipe 9 leading back into the tank A. The delivery tube 8 is made in two separate portions, the main upper section being 65 mounted at its lower end in the upper wall 28 of a casing 29 secured on top of casing 23 and enclosing a liquid-holding or storage chamber 30. The shorter lower section 31 of the delivery tube is 70 mounted in the lower wall of casing 29 so that an open annular passage 32 connects the chamber 30 with the main vertical passage through the delivery tube. The chamber 30 is normally 75 filled with water, the supply of liquid to this chamber being maintained, under low pressure,

in any one of several alternative ways as will be hereinafter described.

The operation of one of these exhauster units will now be described referring more particularly to the diagrammatic showing in Fig. 4. The 5 water jet a projected upwardly with considerable velocity from nozzle 6 passes rather freely through the small lower section 31 of the delivery tube but tends to disperse so as to more completely fill the upper section 8 of the delivery tube. The 10 fluids b in the exhausting chamber 7 are sucked upwardly by the jet a and partially entrained therewith. The body of water c in chamber 30 tends to flow inwardly through annular passage 15 32 into the delivery tube, and the upwardly flowing jet a also tends to draw water inwardly through this passage. On the other hand, the higher pressure in the delivery tube against which the jet is projected tends to resist this inward flow of water through passage 32, and at times 20 actually forces the water outwardly as the outward lateral pressure at this point rises. As the result of these opposing and substantially balanced forces a ring or elastic throat of water is maintained within the delivery tube adjacent the 25 passage 32 and serves to furnish a lining or envelope of water within the lower portion of delivery tube 8 which merges with the water of the jet as the combined fluids pass upwardly through the delivery tube and are discharged into the 30 pipe 9. While there will normally be a withdrawal of liquid from chamber 30 to maintain 35 this ring or throat of water and the water lining or envelope within tube 8, this discharge of water will be quite small as compared with the volume 40 of water furnished to the upwardly flowing stream by the jet a. The fluids b sucked upwardly from chamber 7 are not only entrained between the dispersed water particles of the jet a but are also entrained between the jet and the liquid envelope 45 furnished by ring d and the enclosing water envelope that moves upwardly with the jet. As a consequence, violent frictional engagement with the stationary walls of the delivery tube is minimized. This feature of the operation may be better explained by referring to the familiar formation of bubbles of water upon the surface of water in an open rain barrel. These bubbles form due to the entrainment of air by water flowing into the barrel, the drops of water striking the surface of the water in the barrel and entrapping air particles due to the action of cohesion resulting from the viscosity of the water. These bubbles float upon the surface of the barrel with the air securely entrapped in the film of water surrounding them until the bubbles strike the sides of the barrel whereupon they break and the entrapped air is lost. In this exhauster this principle is used to entrap air particles in the dispersed water of the upwardly flowing jet, and instead of 50 striking the walls of the delivery tube and thus releasing the air, the gas-carrying water particles are surrounded by an envelope of water at d which is elastic and moves upwardly with the liquid stream thus minimizing the release of the 55 entrained gas until the stream has passed upwardly into the area of higher pressure. The surrounding water throat d will automatically adjust its diameter in accordance with pressure changes in this portion of the delivery tube thus 60 providing a more steady and continuous sucking action on the fluids b in chamber 7 and minimizing the effect of pressure variations in the jet and in the space into which the fluids are projected. This apparatus is adapted to handle a 65 70 75 80 85 90 95

gas-vapor mixture of fluids *b* which may consist in varying proportions of air or non-condensable gases, condensable vapor, and dispersed liquid particles. The variation in the proportion 5 of these materials, as well as the pressure change caused by condensation of a portion of the vapor all tends to create pressure fluctuations in the delivery tube and these are compensated for by the elastic liquid ring or throat *d* so as to provide a 10 more steady and efficient operation.

In the forms of apparatus shown in Figs. 2, 3, 5, 6, 7 and 8 the water supply in chamber 30 which furnishes liquid for the elastic ring *d* is replenished from the condensate which flows into exhausting chamber 7 and then collects in the bottom portion 33 of this chamber. A passage 34 leads upwardly from chamber 33 through strainer 35 into chamber 36 which is connected through restricted passage 37 with chamber 38 communicating at 39 with the water supply chamber 30. The exit end of passage 37 is closed by a swinging valve 40 carried by lever 41 pivoted at 42. This valve permits the upward flow of water from collection chamber 33 into supply chamber 30 (this upward flow being created by the suction of the jet) but prevents the return flow of water from the upper chamber 30. Some of the condensate which drains into chamber 7 will be drawn through this outside valve passage to supply the 20 liquid for the enveloping throat *D*, while the remainder of this condensate will be drawn up by the jet and discharged through the delivery tube along with the entrained gases. It will be noted that the water is drawn into the storage space 30 by the suction produced by the jet and is, therefore, under low pressure and there is never any substantial pressure tending to force the water inwardly through the annular passage 32. The one-way valve 40, as well as the back-pressure 25 set up by the restricted passage 37, tend to prevent the return flow of liquid from chamber 30 under the influence of gravity or an abnormal increase of the pressure of the jet. In this manner a supply of water under quite low pressure is maintained in and about the annular passage 32, and the lateral pressures at the inner and outer sides of this passage are normally substantially balanced.

In the modification shown in Fig. 9, condensate delivered into exhausting chamber 7 drains into the chamber 43 having a port 44 leading into passage 45 through which liquid is drawn upwardly into chamber 30. A valve 46 which closes the inlet end of port 44 is carried by one arm of a bellcrank 47 pivoted at 48, the other arm of this bellcrank carrying a float 49. When the liquid level in chamber 43 is low, the valve 46 will be moved to closed position to cut off the flow of liquid through passage 45. When 50 sufficient liquid has accumulated in chamber 43, the float 49 will open the valve and permit liquid to be drawn up through passage 45 into chamber 30. With this float arrangement it is possible to make the opening for the flow of water proportional to the rate at which the water accumulates in chamber 43. Also when no water is accumulating the valve is closed to store the water in chamber 30 and passage 45.

In the simpler form of the invention shown in Fig. 1, the chamber 33 which supplies the liquid ring *d* is connected directly through pipe 50 with the water supply within tank A. Pipe 50 is preferably provided at some intermediate point with a restricted orifice to control the flow of water 55 to chamber 30. Since the storage chamber 30

is positioned at a height near the normal water level in tank A, and the restricting orifice in pipe 50 limits the rate of flow therethrough, the supply of water in chamber 30 will be replenished as required but will remain under the desired low 10 pressure. This form of the invention is preferable where the apparatus is to operate under a high vacuum with little or no condensate returning from the heating system, that is the fluids to be exhausted are mostly gaseous.

In the forms of apparatus shown in Figs. 5 to 9 inclusive, a second auxiliary delivery tube section 51, quite similar in form to the auxiliary section 31 previously described, is interposed between section 31 and the main section 8 of the delivery tube. This second tube section 51 is mounted in a web 52 which divides a portion of chamber 30 into the lower chamber 30' and the upper chamber 30''. Passages 32' and 32'' communicate with the delivery tube between the auxiliary sections 31 and 51, and the sections 51 and 8 respectively so as to provide two separate rings or throats of liquid within the entrance portion of the delivery tube. The advantage of this two-stage system is that it increases the area 20 of the portion which has liquid walls or substantially elastic walls, and provides two rings of water instead of a single one so that a better enveloping action is obtained. It has been found that this two-stage construction increases the 25 efficiency of the apparatus, and it should be understood that two or more such sections may be used if found desirable.

In the modification shown in Fig. 8 the intermediate tube section 51', instead of being fixed 35 in the web 52 is vertically slidable therethrough between the limits determined by the collars 53 and 54 so that the section 51' can automatically adjust itself vertically in response to the pressures acting thereon so as to properly proportion the 40 liquid flow through the annular passages 32' and 32''. The parts will be so designed with relation to the weight of member 51' and the pressure of the upwardly flowing liquid stream that this movable tube section will float between the 45 opposing forces and properly distribute the flow of water to the two liquid rings. Preferably the web 52 will be provided with an orifice 52' for restricting the flow of water into chamber 30'' thus providing a time interval to elapse before 50 the equalizing of the pressures in the two chambers 30' and 30'' so that the sliding portion of the delivery tube will be permitted to react to the difference in pressure.

It will be understood that this two-stage form 55 of delivery tube can be used with either a single jet exhauster element or with each of a multiplicity of jets as shown in any of the various modifications.

In the modification shown in Fig. 10, the 60 nozzle 6' is provided with a plurality of separate outlets 55 so as to project a plurality of separate jets upwardly into a single delivery tube (which may be provided with either one or a plurality of auxiliary sections as hereinabove 65 described.) The operation of this form of the invention is the same as already described except that additional suction space and entrainment surface is provided between the several separate streams or jets. All of these jets are surrounded 70 by the envelope of water within the delivery tube.

In the form of apparatus shown in Fig. 11, four separate similar exhausting units are grouped in close proximity as indicated by the four separate auxiliary delivery tube sections 31^a, 31^b, 75

31^c, and 31^d. Instead of having each of these units supplied with water from a single chamber 30, the casing is provided with interior webs so as to divide the chamber into four separate supply chambers 30^a, 30^b, 30^c, and 30^d, one for each of the units. These chambers are separately supplied with water through manifold 56 and passage 57 from any of the sources of supply as hereinabove described. The ports 37^a, 37^b, 37^c, and 37^d leading to the respective chambers 30^a, 30^b, 30^c, and 30^d from manifold 56 may be each separately controlled by the check-valves 40^a, 40^b, 40^c and 40^d, respectively. Since each of the elastic rings has its own source of water supply 15 pressure fluctuations in one of the units will have no direct effect upon the pressures in an adjacent unit as might be the case if all drew their water supply from a single chamber.

In any of the forms of construction hereinabove disclosed, instead of supplying additional water continuously or intermittently through the chamber 30 by any of the methods already described, this chamber 30 might be made closed or "dead end" so that water would be stored 25 therein upon a rise in pressure in the delivery tube and released when the pressure falls. In other words, the supply of water in this chamber would be furnished from the stream flowing through the delivery tube. Such an apparatus 30 is not as efficient as the forms hereinabove described but it is more efficient than the ordinary type of jet exhauster. It is also possible in a system such as disclosed in Fig. 2 to omit the one-way valve 40 (or the control valve 46 as shown 35 in Fig. 9) with a small sacrifice in the amount of vacuum obtainable with the apparatus.

It will be noted that in all forms of the invention a storage space for a supply of water is provided around the annular opening leading into 40 the throat of the delivery tube, this supply being, however, under quite low pressure. The flow of water, one way or the other, through the annular opening 32 will depend upon variations in the suction or pressure of the jet, a substantial balance of pressures being normally maintained in the throat portion of the delivery tube. Normally there will be a rather small flow of water through passage 32 and into the throat of the delivery tube to maintain the liquid lining. 45 It is most convenient to attain these results by projecting the jet upwardly, as in the forms of apparatus herein disclosed, so that the action of gravity on the water supply may be more easily controlled. It is possible, however, to operate 50 the jets downwardly, or in any direction, in which case the supply of water for the throat must be restricted and controlled so as to maintain the necessary balance of pressures.

An exhausting apparatus of this general type 60 has been found to be especially effective and advantageous when used for withdrawing mixed fluids (gases and liquids) for example in exhausting the fluids from the return line of a heating system. As compared with jet exhausters heretofore used (each equipped with the same size motor) an increase of more than 100% in air capacity has been obtained when exhausting air and condensate simultaneously, and an increase of more than forty percent when exhausting air 65 alone. It may be noted that the apparatus does not operate primarily by condensation of the vapor to produce a vacuum, but operates on the kinetic principle, that is the mechanical withdrawing of the fluids from the space to be exhausted. Such condensation as does occur en-

hances the exhausting action, and this condensing action may be increased by supplying the actuating water at colder temperatures. In this manner a combined condenser and air pump is provided. 5

Although a centrifugal pump has been shown as supplying the water under pressure to form the actuating streams or jets, it is to be understood that any other means of providing water under pressure could be utilized with this improved type of exhauster. 10

This improved exhauster insures reliable starting of the exhausting action after a period of disuse, and this is important since an exhausting apparatus of this type is used intermittently. 15 With the ordinary type of jet exhauster there is a tendency when starting for the actuating jet water to shoot through the delivery tube without adhering to the walls and sealing them so as to prevent the return of air particles from the region of higher pressure into which the fluids are projected. The elastic liquid throat provided in the delivery tube joins with the water of the jet to insure a proper sealing of the tube and prevents a breaking down of the suction as well as 20 making more effective the entrainment of the gas particles. The water envelope provided within the delivery tube from a source separate from the jet acts in effect as an elastic delivery tube capable of varying its internal dimensions 25 as well as changing its contour as required by the flow conditions prevailing at any time. 30

I claim:

1. A jet exhauster comprising a chamber into which fluids to be exhausted are delivered, a 35 nozzle projecting into the chamber, means for forcing a jet of liquid under pressure through the nozzle, a delivery tube leading from the chamber into which tube the jet is projected, a liquid-holding chamber surrounding the entrance portion of the delivery tube, means for supplying liquid to this chamber, there being a pair of spaced apart annular openings in the delivery tube surrounding the passage therethrough and communicating with this chamber, the portion of 40 the tube between the annular openings being movable to adjust the relative sizes of the annular openings.

2. A jet exhauster comprising a chamber into which fluids to be exhausted are delivered, a 50 nozzle projecting into the chamber, means for forcing a jet of liquid under pressure through the nozzle, a delivery tube leading from the chamber into which tube the jet is projected, a liquid-holding chamber surrounding the entrance portion of the delivery tube, means for supplying liquid to this chamber, there being a pair of spaced apart annular openings in the delivery tube surrounding the passage therethrough and communicating with this chamber, the portion of 55 the tube between the annular openings floating between the adjacent liquid streams to automatically adjust the relative sizes of the annular openings.

3. The method of exhausting a mixture of 65 gases and liquids from an enclosed space which consists in entraining this mixture between liquids furnished by a jet projected through the space and an annular body of liquid maintained under substantially balanced lateral pressures 70 around the exit from the space and through and in contact with which the jet is projected, the liquid supplying the annular body being drawn by the suction of the jet against the action of gravity from liquids delivered into the space. 75

4. The method of exhausting a mixture of gases and liquids from an enclosed space which consists in entraining this mixture between liquids furnished by a jet projected through the space and an annular body of liquid maintained around the exit from the space and through and in contact with which the jet is projected, the pressure of the annular body of liquid being so controlled that the inward pressure of the annular body of liquid and the opposing lateral pressure of the jet are substantially balanced so as to provide an elastic liquid throat about the jet.

5. The method of exhausting a mixture of gases and liquids from an enclosed space which consists in entraining this mixture between liquids furnished by a jet projected upwardly through the space and an annular body of liquid maintained above the space and around the exit therefrom, and through and in contact with which annular body of liquid the jet is projected, the pressure of the annular body of liquid being so controlled that the opposed lateral pressures of the jet and annular body of liquid are substantially balanced.

6. The method of exhausting a mixture of gases and liquids from an enclosed space which consists in entraining this mixture between liquids furnished by a jet projected upwardly through the space and an annular body of liquid maintained above the space by the suction of the jet and through and in contact with which the jet is projected.

7. A jet exhauster comprising a chamber into which mixed fluids to be exhausted are delivered, a nozzle projecting upwardly into the chamber, a delivery tube leading upwardly from the chamber in line with the nozzle, means for forcing a jet of liquid upwardly through the nozzle and chamber and into and through the delivery tube, a liquid storage chamber above the first-mentioned chamber and surrounding the lower portion of the delivery tube, there being an annular opening surrounding the passage through the tube and leading from the storage chamber into the entrance portion of the tube so that liquid may pass through this opening to form a liquid lining for the tube, fluids from the first-mentioned chamber being entrained between the liquids of the jet and lining, a restricted passage leading from the first-mentioned chamber to the storage chamber through which passage liquid is drawn upwardly by the suction of the jet to maintain the supply in the storage chamber, and a one-way valve in the passage opening only toward the storage chamber.

uids of the jet and lining, and means for maintaining a supply of liquid under low pressure in the storage chamber.

8. A jet exhauster comprising a chamber into which mixed fluids to be exhausted are delivered, a nozzle projecting upwardly into the chamber, a delivery tube leading upwardly from the chamber in line with the nozzle, means for forcing a jet of liquid upwardly through the nozzle and chamber into and through the delivery tube, a liquid storage chamber above the first-mentioned chamber and surrounding the lower portion of the delivery tube, there being an annular opening surrounding the passage through the tube and leading from the storage chamber into the entrance portion of the tube so that liquid may pass through this opening to form a liquid lining for the tube, fluids from the first-mentioned chamber being entrained between the liquids of the jet and lining, and a restricted passage leading from the first-mentioned chamber to the storage chamber through which passage liquid is drawn upwardly by the suction of the jet to maintain the supply in the storage chamber.

9. A jet exhauster comprising a chamber into which mixed fluids to be exhausted are delivered, a nozzle projecting upwardly into the chamber, a delivery tube leading upwardly from the chamber in line with the nozzle, means for forcing a jet of liquid upwardly through the nozzle and chamber into and through the delivery tube, a liquid storage chamber above the first-mentioned chamber and surrounding the lower portion of the delivery tube, there being an annular opening surrounding the passage through the tube and leading from the storage chamber into the entrance portion of the tube so that liquid may pass through this opening to form a liquid lining for the tube, fluids from the first-mentioned chamber being entrained between the liquids of the jet and lining, a restricted passage leading from the first-mentioned chamber to the storage chamber through which passage liquid is drawn upwardly by the suction of the jet to maintain the supply in the storage chamber, and a one-way valve in the passage opening only toward the storage chamber.

DAVID N. CROSTHWAIT, JR.
